SAILING CATAMARAN

Hobart L. Alter, Laguna Beach, Calif., assignor to Coast
Catamaran Corporation, Capistrano Beach, Calif., a
corporation of California

Filed July 8, 1968, Ser. No. 12,654

Term of patent 14 years

Int. Cl. D12—06

U.S. Cl. D71—1

FIG. 1

FIG. 2

FIG. 3

FIG. 4

FIG. 5

FIG. 1 is a side elevational view of a sailing catamaran showing my new design;

FIG. 2 is a top plan view of said sailing catamaran, the mast and sail being deleted in the interest of clarity;

FIG. 3 is a bottom view of said sailing catamaran, the mast and sail being deleted in the interest of clarity;

FIG. 4 is a front view of said sailing catamaran, the upper portion of the mast and sail being deleted in the interest of clarity; and

FIG. 5 is a rear view of said sailing catamaran, the upper portion of the mast and sail being deleted in the interest of clarity.

I claim:

The ornamental design for a sailing catamaran, substantially as shown and described.
